CONICAL CONTAINER AND METHOD OF
MAKING SAME

John Ernest Page, Sydney, New South Wales, Australia, assignor to Gibson Patent Containers, Ltd., Sydney, New South Wales, Australia, a corporation of New South Wales, Australia

Application February 13, 1939, Serial No. 256,195
In Great Britain February 14, 1938

10 Claims. (Cl. 93—36.1)

This invention relates to conical containers and method of making same, and more particularly to an improved conical container formed from a single blank of paperboard material, which is adapted to hold and contain liquid and granular materials, which may be formed by a relatively few method steps that can be quickly and economically executed.

Conical containers of paper and paperboard materials as heretofore made are particularly weak at the apex end thereof where strength is most desired. The apex end of such prior art containers is neither wholly siftproof nor leakproof since the blank or blanks from which such containers are formed have been previously punctured or cut at the apex point in preparation for the assembly operation.

An object of this invention is to provide an improved conical container which may be economically formed from paper or paperboard or similar sheet materials, which is strong and sturdy in construction, reinforced at the apex end thereof, and which may be made leakproof and siftproof.

Another object of this invention is to provide an improved conical container formed from an uncut and unpunctured blank of paper or paperboard material, which may be suitably treated or coated with a moisture-resistant or oil-resistant compound and which presents a tight unpunctured apex point surrounded by an unpunctured reenforcing skirt that embraces the apex end of the container body.

Another object of this invention is to provide an improved blank from which a leakproof and siftproof conical container may be formed.

Another object of this invention is to provide an improved method of assembling conical container bodies rapidly and economically so as to provide a highly serviceable container which may be manufactured at low cost.

A further object of this invention is to provide a method for forming conical containers comprising a series of folding steps which can be economically performed and which, when completed, provide a container body collapsed in substantially flat condition whereby a series of such containers may be stacked together to occupy a minimum of space during shipment and storage.

A further object of this invention is to provide an improved leakproof and siftproof container for liquid, granular or powdered materials, having a leakproof apex reenforcing and a sealed closure at the enlarged end of the body

which may be conveniently applied after the contents have been inserted, which is strong and rigid in construction, which is economical to produce and tamper-proof, access to the contents being had by severing the apex end of the conical body to provide a convenient pouring spout or opening through which the contents may be discharged.

Other objects of this invention will become apparent as the disclosure proceeds.

In accordance with this invention, a blank formed from suitable paper or paperboard material having the requisite toughness and flexibility is provided, which blank may be treated on one or both surfaces thereof with any desired liquid-proof or grease-proof coating. The blank forming the container body comprises a generally tapered body portion which terminates at the apex end in an uncut and unpunctured end portion which forms a continuous skirt surrounding the apex point and integrally joined to the body portion of the blank. The body portion of the blank is supplied with a suitable adhesive which may be applied in strip form along one side of the blank, which adhesive strip extends across the end portion, the adhesive being preferably applied to the inside face of the blank.

The body portion is folded into tubular or conical form with the side edges thereof arranged in adhesively secured overlapping relationship to provide a generally conical body portion. The end portion is then folded or wrapped around the lower end of the body portion with the apex point as a center so as to provide an enclosing skirt embracing the lower end of the body portion. It will be particularly noted that the apex point and the surrounding skirt is neither cut nor punctured, providing in effect an impervious, unpunctured and uncut cup into which the lower end of the body portion extends and is integrally secured. Thus a conical container is provided, which may be made wholly leakproof and siftproof, and which is provided with substantial reenforcing at the apex end of the container body where strength is especially desired, the surrounding skirt formed from the end portion also serving to maintain the container body in the desired tubular form.

The container body may be made from the prepared blank by winding the blank around a suitable conical mandrel which gives the container body a fixed predetermined conical shape, which winding operation secures the overlapping side edges of the body portion in firm adhesive contact and in addition winds and adhesively

secures the skirt at the apex end to the container body.

As an alternative method, the prepared blank may be folded in the flat by folding one section of the body portion and end portion over the other half section, then folding the securing flap extending along the side edge of the body portion over and into adhesive contact with the adjacent body section, and then continuing to fold the resultant folded skirt around the reduced end of the body portion, which folded skirt becomes firmly secured to the reduced end of the body portion by adhesive previously applied thereto.

A further method of assembly, which combines both methods above enumerated, may also be employed. In this method of assembly, one half section of the blank is folded over the other half section, the glued securing flap along one side of the blank is folded over and pressed into adhesive contact with the adjacent section; the thus folded blank is then expanded into a generally tubular form and telescoped over the end of the conical mandrel, and the skirt then wound around and adhesively secured to the reduced end of the body portion.

Thus it will be noted that when the assembly operation on the container bodies has been completed, they may appear as fully expanded conical bodies which may be arranged in nesting relationship to occupy a minimum of space, or they may be so formed as to produce a container body in flat collapsed form which then may be conveniently stacked one upon another so as to occupy a minimum of space, which collapsed bodies may be ready for immediate use to receive contents by expanding the same.

The conical container bodies thus formed may be used, if desired, as drinking cups to hold either hot or cold liquids. If it is desired to ship or store the contents in the container bodies, a suitable closure member may be applied and sealed to the enlarged end thereof, so as to hold the contents therein in a leakproof manner. Access to the contents may be had either by removing the closure disc or portion thereof, but preferably the sealed container is opened by severing the apex end from the container body so that the reduced end of the container body thus severed provides a highly convenient and practical pouring spout for ejection of the liquid or powdered contents. The sealed cone-shaped container thus formed is highly adapted to contain such products as lubricating oils, in which the oils are contained in a leakproof manner fully sealed and closed against tampering, and when the apex end is removed the reduced pouring end provides a convenient funnel-shaped spout through which the oils may be ejected into the crankcase of an automobile engine or other power engine without the provision of funnel equipment and without spillage or loss of the contents. My improved sealed container is also highly adapted for containing milk, fruit or vegetable juices, or other edible or non-edible liquids, granular, or powdered materials. If only a fraction of the contents is to be used at one time, the apex end of the sealed container upon removal may be inverted and inserted into the opening in the end of the body portion to serve as a temporary stopper, preventing contamination or evaporation of the contents.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a face view of a prepared paper or paperboard blank from which my improved conical container is formed;

Fig. 2 is a perspective view of the prepared blank shown in Fig. 1 in the process of being wound over a conical mandrel and illustrates a step in the method of forming the container;

Fig. 3 is a perspective view of the conical mandrel and container-forming blank illustrating a further step in the formation of the container;

Fig. 4 is a perspective view of the conical container body as it appears when completed and removed from the mandrel;

Fig. 5 is a perspective view of a plurality of conical-shaped container bodies arranged in nested relationship, so as to occupy a minimum of space during shipment and storage;

Fig. 6 is an elevational view of the conical container body showing an end closure applied thereto, certain parts being broken away to illustrate certain details of the construction;

Fig. 7 is an elevational view of the container body showing a closure of somewhat modified form applied thereto, certain parts being broken away to illustrate certain structural details;

Fig. 8 is a perspective view of the container shown in Fig. 6 having the tapered end severed from the container body to provide a pouring opening for the container, this view showing the conical end inserted into the pouring opening in inverted position to provide a temporary closure therefor;

Fig. 9 is a face view of a prepared paper or paperboard blank from which a conical container body of somewhat modified construction may be formed;

Fig. 10 is a perspective view of a plurality of completed conical containers, each formed from the blank shown in Fig. 9 by a simple folding operation which produces a collapsed substantially flat container body, a plurality of which may be stacked together in collapsed condition to conserve shipping and storage space;

Fig. 12 is a perspective view of the blank shown in Fig. 11 having opposed sections of the blank folded together in superimposed relationship, illustrating the initial step of an alternative method of assembly;

Fig. 13 is a perspective view of the folded blank shown in Fig. 12 having applied thereto a further step in the alternative method of assembly;

Fig. 14 is a perspective view of the folded blank shown in Fig. 13 telescoped over a conical mandrel ready to receive a further winding and body forming operation; and

Fig. 15 is a perspective view of the blank and mandrel at the completion of the container body forming operation.

Similar reference characters refer to similar parts throughout the several views of the drawings and the specification.

The container forming blank from which the conical shaped container body is formed is par-

ticularly adapted for assembly from a flexible paper or paperboard sheet of the requisite tensile strength to serve the purpose intended. The paper or paperboard blank is preferably formed from a high-grade kraft paper having substantial body, the thickness of the sheet varying from paper having a thickness comparable to that of wrapping paper to a fiberboard having a thickness up to $\frac{1}{16}$ inch or more in cases where the container is to be of substantial size and to contain products of substantial weight. An important characteristic of my improved container is its leakproof and siftproof qualities, and thus it is admirably adapted for containing liquids such as milk or oils, among others, as well as fine granular materials. The body-forming blank may be treated with a suitable coating so as to render the same liquid-proof and grease-proof, which coating may be applied either to the interior or exterior surface thereof, or to both interior and exterior surfaces, either while the sheet is in blank form or after the sheet has been formed into a completed conical container body.

The container forming blank, as shown in Figs. 1, 9 and 11, comprises generally a body forming portion 1 of generally tapered shape, the reduced end of which terminates in a bottom forming portion the center of which forms the apex of the completed conical container body. This end portion forms an important feature of my improved container forming blank, since it will be noted that this end portion is not cut or punctured in any manner or form, so that when a blank having the proper moisture-proof and grease-proof qualities is formed into the desired conical container body, the apex end, where leaks normally occur in the prior art conical container bodies, is positively liquid-tight.

The body-forming blank A, as shown in Fig. 1, comprises a body forming portion 1 having side edges 4 and 5 thereof tapering downwardly, with the reduced end of the body portion 1 terminating in an apex forming portion 2 the approximate center 3 of which forms the apex end of the container body. A fold line 13 extends from the apex point 3 along one side edge of the blank substantially parallel to the side edge 5 so as to define a securing flap 12 between the fold line 13 and the side edge 5 of the blank. The end portion 2 is preferably defined by a curvilinear or generally spiral shaped edge 8 which intersects the side edge 4 of the body portion at 6 and the side edge 5 of the body portion at 7. A strip of adhesive *a* is applied to the inside face of the blank adjacent the side edge 4 thereof, which strip of adhesive is of such width as to define an edge section 10 designed to overlap the securing flap 12 and a part of the body portion 1. The inner edge of the overlap section 10 is indicated by the line 11 extending substantially parallel to the side edge 4 and intersecting the apex point 3. The interior surface between the fold line 13 and the line 11 forms the interior surface of the conical body.

An imaginary straight line 9 is shown drawn across the face of the blank through both the body portion 1 and the end portion 2, so that the acute angle designated *x* between the imaginary line 9 and the imaginary line 11 is the same as acute angle *x* between the imaginary line 9 and the fold line 13. That section of the end portion to the right of the imaginary line 9 has been designated 2' and that section of the end portion to the left of the imaginary line 9 has been designated 2''. The strip of adhesive *a* extending

along the side edge of the body portion 1 may be made to continue in a substantially straight line across part of the end portion 2, as at *a'* illustrated in Fig. 1. The wide edge of the body portion 1 may have a generally curvilinear contour 100, so that when the container body is formed a substantially flat top edge is provided for the completed container body.

Blanks of the type shown in Fig. 1 are admirably adapted for formation into conical container bodies adapted to contain oily products, such as lubricating oil, and may be made of such size as to contain a quart or more of such oil. In making a container to contain, say, a quart of oil, the blank may be so cut as to provide a conical container body whose larger end has any desired diameter, but preferably the larger end should be from 4 to 6 inches in diameter and the container body from 6 to 12 inches in length when made to contain a quart of contents. It will be appreciated, however, that the conical pitch of the container may be varied within relatively wide limits as desired to conform to shipping, storage and marketing conditions and requirements.

In forming a container for oils, it is preferable to coat the interior of the heavy paper or fiber blank with a suitable oil and grease resistant coating, such as a liquid flowable cellulose lacquer or other known oil and grease resistant coatings, before the blank is assembled in container form, and it is desirable to apply such a coating to both the interior forming and exterior forming surfaces of the blank. Where such an oil resistant and grease resistant coating is used, it has been found that the strips of adhesive *a* and *a'* may comprise a suitable solvent or softening component for such coating materials, so that the coating itself when in soft or plastic condition will serve to obtain firm adherence between flap 12, the body portion and the overlapping section 10. It is appreciated, however, that other glue or adhesive compounds known in the art may be used and applied to the blank as above indicated for causing the securing flap 12 and the overlapping section 10 to firmly adhere, and also to cause the overlapping section 10 to firmly adhere to the exterior surface of the body which it overlaps, as shown in Fig. 4.

The blank shown in Fig. 1 may be easily and quickly shaped into a conical container body by winding the same around a suitably shaped conical mandrel M in the manner illustrated in Figs. 2 and 3. In performing this assembly operation, it is preferable to fold the securing flap 12 backwardly over the exterior of the body portion 1 before the blank is applied to the mandrel M. The blank is so arranged that the apex end *p* of the mandrel M is positioned adjacent the apex forming point 3 of the blank. A suitable clip *e* fixed to the mandrel M may be provided for gripping and holding one side edge of the blank adjacent the wide end thereof to the mandrel. The conical surface *s* of the mandrel may be covered with a frictional surface, such as soft rubber, and may be roughened or corrugated to prevent the blank from slipping. The blank is wound around the mandrel M, either by turning the mandrel M by suitable driving means and holding the blank by means of some suitable relatively stationary but flexible element in hugging contact with the mandrel, or by holding the mandrel M stationary and providing a suitable moving element for winding the blank around the same. The mandrel M is of such size and shape

as to define the desired interior surface of the conical container body.

When the body portion 1 has been wound completely around the mandrel, the securing section 10 will overlap and adhere to the rebent securing flap 12 and to the adjacent exterior section of the body portion 1, as clearly shown in Figs. 3 and 4. When this has been accomplished, the end section 2' will have been brought into overlapping relation to the interior surface of the end section 2' which has previously received the adhesive, so that a double-ply end portion or skirt, as shown in Fig. 3, will be formed. With continued winding of the blank around the mandrel, the double-ply skirt will continue to be wound around the apex end of the conical container body. Adhesive, glue or other tenacious binder 'a'' is applied to the exterior surface of the end section 2' either while the blank is in flat expanded form, as shown in Fig. 2, or during the winding operation. The glue or adhesive 'a' causes the end portion to firmly adhere to the apex end of the body portion 1, so that when completed the conical container body has at least a full double-ply wrap around the apex end thereof, as shown in Fig. 4. Thus the end portion 2 when fully formed provides an unpunctured cup forming an integral part of the body portion 1 and into which the body portion extends. By cutting the end portion 2' so as to provide an exterior edge 8 of the proper curvilinear or substantially spiral shape, this edge 8 of the end portion wound around the apex end of the body portion will provide a smooth and even shoulder, as shown in Figs. 4 and 5. The free edge 9 of the end portion is unscored and unbroken and the apex end 3 is also unpunctured, so that when the sheets forming the blanks are properly treated with moisture or grease resistant coating, a fully liquid-proof, oilproof and grease-proof container is provided.

The liquid-proof and grease-proof coating applied to the interior surface of the blank forms a liquid-tight and oiltight seal at the joint y, as shown in Fig. 4, and this is particularly true where a coating is used which is rendered plastic or soft by a suitable solvent or a softener therefor (herein also referred to as an adhesive), since this softener permits the subjoined coated surfaces of the overlapping section 10 and the securing flap 12 of the adjacent section of the body portion to flow together to form a liquid and oiltight bond. It is also appreciated that after completion of the container bodies they may be sprayed with or dipped in the desired coating solution to render them liquid-tight and oiltight. Where milk or other foodstuffs are to be packed in the container bodies, a wax coating applied while the wax is in molten form has been found satisfactory. Where oily or greasy materials are to be packed in the container, other coating substances may be employed, such as cellulose ester, lacquer or a resin, or a phenolic compound applied in liquid or plastic form.

As shown in Fig. 6, the upper end of the container body A, after the contents C have been inserted therein, may be closed and sealed by a suitable closure, which may comprise a closure member 15 formed of metal or paperboard which is provided with an upstanding shoulder or rim 16 seating within the mouth of the container. The upstanding rim 16 merges into a downwardly extending flange 17 positioned exterior to the container body, which flange terminates in an in-turned lip 18 which seats under or is crimped to

a rolled edge formed on the container body, which rolled edge comprises an outturned and reverse turned flange 19 and an end portion 20 seating between the flange 17 and the body 1 of the container. The rolled edge of the container body comprising the portions 19 and 20 may be formed by a rolling or spinning operation customary in the art, and the closure disc 15 may be crimped to this rolled edge by a crimping operation, so that the closure disc 15 is permanently and fixedly secured and sealed to the mouth of the container body in a leakproof and siftproof manner.

In the form shown in Fig. 6, the contents may be removed by forcibly removing the closure disc 15 or, if desired, the closure disc 15 may be provided with a suitable discharge outlet 21 of suitable size to permit the liquid or granular contents C to be readily removed. The discharge outlet 21 may be closed by a suitable cap member 23 having a downward-turned flange or rim 24 which grips the upturned rim or flange 22 surrounding the discharge outlet 21.

A further alternative form of body closure is illustrated in Fig. 7, wherein an end closure disc 25, made of metal or suitable paperboard, is provided with a reverse bead or groove around the peripheral edge thereof, into which the inturned flange portion 28 of the container body extends. The reverse bead or groove is formed by peripherally extending inturned rim portion 28 and a peripherally extending outturned rim portion 27 between which the inturned flange of the container body seats, the rim portions 26 and 27 being tightly crimped to the flange portion 28 to provide a liquid-tight and siftproof seal.

Still a further alternative form of body closure may be employed wherein the end closure is spun or crimped to the container body before the contents are inserted, the end closure having an aperture through which the contents are introduced to the container; after the filling operation is completed the aperture in the end closure is sealed.

It will be appreciated that numerous other types of closures known in the art may be employed to close and seal the open mouth of the container body.

Liquid or granular contents having pouring qualities can most conveniently be removed from the conical container by severing the apex end of the conical container body along line 14 adjacent the peripheral edge 8 of the end forming portion. The opening in the apex end of the container thus formed provides an admirable and highly convenient pouring spout from which liquid or granular contents may be removed, the conical container body 1 serving as a pouring funnel. The end closure applied to the large end of the conical body can then be permanently and irremovably applied in a leaktight manner, and since no provision need be made for the removal of the end closure at the enlarged end of the conical body, the same can generally be produced at greater speed and less cost. The pouring spout is formed at the reduced end of the conical body by cutting away the end portion 2, and provides a highly convenient dispensing opening for pouring such liquid materials as lubricating oils into the crankcase of automobile engines, since the reduced pouring spout end of the container can be readily inserted into the oil supply pipe without danger of spillage and without the provision of a pouring funnel commonly employed.

The container is also admirably adapted for

holding milk, fruit juices and other edible liquids and granular materials, all of which can be conveniently poured out of the pouring spout formed by cutting away the end portion 2. As shown in Fig. 8, the end portion 2 can then be inverted and inserted into the reduced pouring opening to provide a temporary cork or stopper, protecting the contents remaining in the container from dust and contamination.

It will be appreciated that my improved container body may be formed and assembled in flat folded condition, as illustrated in Figs. 9 and 10. When this method of assembly is used, a blank A', as shown in Fig. 9, is provided, made similar in shape to the blank A shown in Fig. 1. Score lines 13 and 31, radiating outwardly from the apex point 3 of the end portion, are provided so as to define a reverse fold securing flap 12 between the side edge 5 of the blank and the score line 13 and an overlapping securing flap 10 between the side edge 4 of the blank and score line 31. A substantially straight score line 29 traverses the blank and extends through the body portion 1 and the end portion 2 and is so positioned that the section 33 of the body portion which lies between score lines 29 and 31 is equal in size and dimensions to the body section 33' between the score line 29 and the score line 13. A suitable adhesive, which may be of various materials as above indicated, is applied to the overlapping securing flap 10 between the side edge 4 of the blank and the score line 31, which strip of adhesive also traverses the end portion 2 of the blank to provide adhesive a' to a section of the inside face of the end portion. Adhesive a' is also applied to a section of the outside face of the end portion 2 as indicated by the stipple lines shown in Fig. 9.

When the blank shown in Fig. 9 has been thus prepared, the container body is formed by first folding the body section 33' over the body section 33 along the fold line 29, and by this operation the end section 2'' is also folded over and brought into adhesive contact with the end section 2'. The securing flap 12 also is pressed into adhering contact with the glued face of the securing flap 10 with the score line 13 in registry with the score line 31. The securing flap 10, and with it the securing flap 12, is then bent over so that the glued face of the securing flap 10 is brought into adhesive contact with the outside face of the body section 33', which operation also brings the glued face of the superimposed triangular sections 34' and 34 into adhesive contact with the lower end of the body section 33'. The end portion previously folded into double-ply formation is then folded over the lower end of body section 33 with the triangular section 35' pressed into adhesive contact with the lower end of the body section 33 with the triangular section 35 lying exterior to the triangular section 35'. As folding of the end portion continues, the triangular section 36', to the exterior of which triangular section 36 is adhered, is then folded over the outside face of the securing flap 10 and to any adjacent exposed portion of the body section 33', at the completion of which the end portion has been folded once completely around the lower end of the conical body. Triangular shaped sections 37' and 37, previously folded together into adhesive contact, are then folded over the triangular shaped section 35, as illustrated more particularly in Fig. 10, completing the formation of the container body.

It will be noted that the end portion thus forms

an uncut and unpunctured skirt which surrounds the lower end of the body portion 1, forming in effect an uncut and unpunctured cup into which the body portion extends. It will be particularly noted that the apex point 3 is not cut or severed and the cup forming the skirt is itself completely closed, since the folded edge 29 of the end portion which forms the end of the wound skirt is also unsevered and uncut. The overlapped arrangement of the securing flaps 12 and 10 also forms a leakproof joint in the body portion by reason of the fact that adhesive material fully seals the joint at y.

There is shown in Fig. 11 a blank A'' generally similar in construction to the blank shown in Figs. 1 and 9, the main difference being that the securing flap 12, shown in Figs. 1 and 9, has been eliminated. In this construction, the fold line 51 extends from the apex point 3 radially across the body portion and generally parallel to the side edge 45 thereof. A fold line 29 extends across the body portion 1 and the end portion 2 medially between score line 51 and the side edge 45 of the blank, so as to provide a body section 33 between the score line 29 and the score line 51 equal in size and dimensions to the body section 33' between the score line 29 and the side edge 45 of the blank. Adhesive is applied in a strip a to the securing flap 10 and in a strip a' to the end portion 2. A score line 45' radiates outwardly from the apex point 3 and is generally in line with the side edge 45 of the body portion.

The blank shown in Fig. 11 is formed into conical shape by folding the body portion 33 over the body portion 33' along the score line 29, which operation also folds the end section 2'' over the end section 2', as illustrated more particularly in Fig. 12. Adhesive a' has been previously applied or is then applied to the outside face of the end section 2'', as shown in Fig. 12. In the next step, shown in Fig. 13, the glued securing flap 10 is folded over the adjacent side edge of the body section 33' and a portion of the glued end section 2'' is folded over the reduced end of body section 33' and pressed into adhesive contact therewith, as shown in Fig. 13. Up to this point, the folded blank, as shown in Fig. 13, is in substantially flat collapsed condition. The body portion is then expanded into generally tubular form by exerting compressive pressure on the body portion applied along the fold lines 29 and 51, and the thus expanded tubular body portion is slipped over the conical end of the forming cone M, as shown in Fig. 14. The end portion 2, which provides a double-ply skirt formed by the overlapped end sections 2' and 2'', is then wound around the reduced end of the body portion, as indicated in Figs. 14 and 15. As thus formed, the skirt serves to maintain the body portion in generally tubular or expanded conical form, and when removed from the conical mandrel M, will maintain its generally expanded conical form.

Upon completion of the winding operation shown in Fig. 15, the container body is removed from the conical mandrel M. If edible contents, such as milk, fruit and vegetable juices or other edible products, are to be packaged therein, the conical body may be sprayed with or dipped in a bath of molten wax, which serves to permanently seal the joint y in the body portion so as to make the joint leakproof and siftproof. Where the molten or hot wax is applied to the joint y, it has been found that this molten wax will provide an effective seal to prevent leakage of such

contents as milk, fruit, vegetable juices, and other materials that do not have a dissolving effect on the wax.

The containers illustrated in Figs. 1 to 10 inclusive are well adapted for containing oil. If oils, and particularly lubricating oils, are to be contained in the container, it may be desirable to dip the container body in or spray the interior or exterior of the container body with a grease and oil resistant compound, of which there are several known and available, such as cellulose esters, resins, and various phenolic compounds.

It will be appreciated that the blanks, as shown in Figs. 1, 9 and 11, from which the conical container bodies are formed, may first be treated with the selected liquid or oil resistant coating compound before the same is folded into container form, and where such compounds can be made fluid, plastic or sticky by a solvent or heat, a solvent or heat may be applied during the formation of the conical container body to effect adherence of the overlapping securing flap or flaps and the surrounding skirt to the body portion. It will be further appreciated that either the treated or untreated blanks after formation into the container body may be coated by spraying with or dipping into the liquid resistant or oil resistant compound in a manner well known in the art. It will also be appreciated that the enlarged end of the conical body may be closed by numerous different forms of end closures formed either of metal or paperboard or a combination of metal and paperboard, which may be crimped, rolled, sweated, or otherwise locked or fixed to the upper rim of the container body after the contents have been inserted.

It will be understood that where the term "adhesive" or "glue" is herein used, it is intended to cover any well known glue or adhesive used in the container industry or may also include a solvent for the coating covering the surface of the container forming blank.

While I have disclosed as an example and embodiment of my invention the container forming blank, the conical container, and methods of forming same, the disclosed embodiments are to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed is:

1. A conical container forming blank of sheet material having a body forming portion defined by converging side edges adapted to be arranged in overlapped relationship, and an end portion integral with and wholly unsevered from said body portion, said end portion having parts thereof extending laterally beyond both of the adjacent converging ends of said side edges.

2. A one-piece blank adapted to form a conical container including, a body forming portion having converging side edges adapted to be arranged in overlapped relationship, and an end portion integral with and wholly unsevered from said body portion, said end portion having an unsevered and uncut apex area therein surrounded by an uncut and unpunctured skirt portion circumscribed by a substantially curvilinear edge which extends laterally beyond both of the adjacent side edges of said body portion.

3. A one-piece blank adapted to form a coni-

cal container including, a body forming portion having converging score lines which converge into an uncut and unscored apex forming point, securing flaps hinged to said body portion along each of said score lines adapted to be arranged in overlapping relationship to provide a conical body portion, and an uncut and unpunctured end portion having a skirt surrounding said apex point, said end portion having a generally curvilinear contour whose edges extend laterally beyond both of the adjacent side edges of the body portion.

4. A one-piece blank adapted to form a conical container body including, a body forming portion having converging side edges, a symmetrical end portion integral with and wholly unsevered from said body portion extending laterally beyond the adjacent side edges of the body portion, and a strip of adhesive extending along one side edge of said body portion and across said end portion.

5. The method of forming a conical container body from a paper or paperboard blank having a body portion defined by converging side edges and an end portion wholly unsevered from said body portion extending laterally beyond both of the adjacent side edges of the body portion, which method includes the steps of applying a strip of adhesive to a side edge of said body portion and a section of said end portion, folding said body portion into generally tubular form, folding said end portion to provide a double-ply skirt section and pressing adhesive applied to a side edge into adhering relationship to the adjacent side edge of the body portion, and thereafter wrapping and adhesively securing said double-ply skirt section around the reduced conical end of said body portion.

6. The method of forming a conical container body from a single blank of paperboard material which blank has a body forming portion defined by converging side edges and an unpunctured end portion integrally formed with and unsevered from said body portion, which method includes the steps of, folding one section of said body portion and said end portion over another section of said body portion and end portion along a generally straight fold line, adhesively securing the free edges of said body sections and said end sections together, expanding the thus folded blank, telescoping the same over a conical mandrel, and thereafter wrapping and adhesively securing said end sections around the reduced end of the body portion.

7. The method of forming a conical container body from a single blank of paperboard material which blank has a body forming portion defined by converging side edges and an unpunctured end portion integrally formed with and unsevered from said body portion, which method includes the steps of, folding one section of said end portion over and securing said section to another section thereof, wrapping said body portion around a conical mandrel, adhesively securing the free edges of said body portion together, and thereafter wrapping and adhesively securing said end sections around the reduced end of the body portion.

8. A leakproof and sift-proof container of generally conical form including a body member having a plural-ply reinforcing cup integrally formed with and embracing the reduced end of said body member, said body member and cup being formed from a blank of sheet material

having a body forming portion defined by converging side edges adapted to be arranged in overlapped relationship, and an end portion integral with and wholly unsevered from said body portion, said end portion having parts thereof extending laterally beyond both of the adjacent converging ends of said side edges and a closure member fixedly secured to the enlarged end of the conical body member.

9. A leakproof and siftproof container of generally conical form including a body member having a plural-ply reenforcing cup integrally formed with and embracing the reduced end of said body member, said body member and cup being formed from a blank of sheet material having a body forming portion defined by converging side edges adapted to be arranged in overlapped relationship, and an end portion integral with and wholly unsevered from said body portion, said end portion having parts thereof extending laterally beyond both of the adjacent converging ends of said side edges and a closure member fixedly secured to the enlarged end of the conical body member, said plural-ply reenforcing cup

being severable from the container body to provide a pouring opening at the reduced end.

10. A leakproof and siftproof container of generally conical form including a body member having a plural-ply reenforcing cup integrally formed with and embracing the reduced end of said body member, said body member and cup being formed from a blank of sheet material having a body forming portion defined by converging side edges adapted to be arranged in overlapped relationship, and an end portion integral with and wholly unsevered from said body portion, said end portion having parts thereof extending laterally beyond both of the adjacent converging ends of said side edges and a closure member fixedly secured to the enlarged end of the conical body member, said plural-ply reenforcing cup being severable from the container body to provide a pouring opening at the reduced end and being of substantial body thickness so that inverted and inserted into said pouring opening it provides a temporary closure stopper for said container.

JOHN ERNEST PAGE.
